UNITED STATES PATENT OFFICE

JOHN P. CARELL, OF TROY, NEW YORK

SUNKEN-VESSEL-LOCATING DEVICE

Application filed February 7, 1929. Serial No. 338,197.

This invention relates to sunken ship locating devices and pertains particularly to a device which acts after the sinking of the boat in the nature of a buoy.

5 The primary object of this invention is to provide a sunken ship locating device which employs a float device normally carried with the ship and releasable therefrom to carry to the surface a thin cable or cord.

10 The float device released from the carrier upon reaching the surface acts as a buoy so that rescue ships may accurately locate the position of the sunken vessel and in addition acts to carry to the surface of the water 15 a light cord or cable connected with the sunken vessel and by means of which a heavier cable carried by the vessel may be drawn to the surface by rescue ships so that contact may be immediately established between rescuers and the sunken vessel.

20 Another object of the invention is to provide a float carrying receptacle which is normally maintained closed and which may be, in the event that the device is used in association with a submarine, readily opened from the interior of the vessel for the release of the float.

25 The invention will be best understood from a consideration of the following detailed description taken in connection with the accompanying drawings forming a part of this specification, with the understanding, however, that the invention is not confined to any strict conformity with the showing 30 of the drawings but may be changed or modified so long as such changes or modifications mark no material departure from the salient features of the invention as expressed in the appended claims.

35 In the drawings:

Figure 1 is a view in side elevation of the vessel locating device embodying the present invention showing the same in applied 40 position;

Figure 2 is a vertical sectional view through the structure;

Figure 3 is a plan view of the float containing receptacle showing the cover in closed position;

Figure 4 is a top plan view of the receptacle with the float removed and showing the cover opened.

50 Referring to the drawings in detail, it will be seen that the device embodying the present invention has been shown mounted upon the body of the vessel, a portion of which is indicated generally by the numeral 1. This body of the vessel may be a portion of a submarine vessel or a vessel of the surface type, 55 in either case the installation of the device will be the same with one exception and that is when the device is installed upon a submarine vessel the control arm for the float receptacle, hereinafter described in detail, 60 will extend downwardly through the wall of the vessel to the interior so that it may be manipulated by persons imprisoned therein.

65 The device comprises an upright receptacle 2 which is preferably, though not necessarily 70 of cylindrical formation. This receptacle may be suitably secured in the upright position described upon the body of the vessel, as for example by the use of brackets 3 and the lower edge thereof is provided with a series of openings 4, which will permit water to readily flow thereto when the receptacle is submerged.

75 The receptacle 2 has cut longitudinally therein from the top edge, the slot 5 and 80 there is located adjacent the receptacle a suitable holder 6 for a coil of cable or chain 7, one end of which is extended into the receptacle 2 through the slot 5.

85 At a suitable point on the exterior face of the wall of the receptacle 2 and at the top thereof there is secured an L-shaped bracket 8, one arm of which extends laterally, as indicated at 9, with the top surface flush with the top edge of the receptacle.

50

85

90

Overlying the top of the receptacle 2 is a cover plate 10, from the periphery of which there extends a hinge arm 11, which is pivotally secured at 12 to the arm 9 of the bracket 8.

Secured to the outer face of the wall of the receptacle 2 at a point substantially one-fourth the way around the receptacle from the bracket 8 is a superposed pair of control shaft supporting brackets 13, these brackets having extending therethrough in substantially parallel relation to the wall of the receptacle a control shaft 14, the lower end of which may extend downwardly through the body of the vessel 1 when the device is used upon a submarine terminating at its lower end in a control handle 15. The upper end of the shaft 14 is extended at right angles to form the crank arm 16, the terminus of which is turned upwardly as at 17 for pivotal engagement with one end of a link member 18, the other end of the link being pivotally secured by the bolt and sleeve unit 19 to the cover 10 at a point along the edge thereof, substantially diametrically opposite the point adjacent which the shaft supporting brackets 13 are located when the cover is closed over the receptacle.

It will be seen from the foregoing description that upon rotation of the shaft 14 to swing the crank 16, the cover 10 will be swung to one side about the pivot 12, this swinging movement being toward the shaft 14. To permit the cover to swing without interference by the shaft there is formed in the cover the arcuate slot 20, the arc of which is struck from the center of the pivot 12 and which has, of course, a radius which is equal to the distance between the pivot 12 and the pivotal center of the shaft 14.

Housed within the receptacle 2 is a hollow float body, indicated generally by the numeral 21. This float may be constructed of any suitable material, such as suitably water-proofed cork or the like and is formed hollow and in two detachably connected sections. Within the float there is mounted upon a shaft 22 a reel 23 which is designed to carry a quantity of light cable 24, which cable passes through a suitable aperture 25 in the body of the float and is connected to the end of the heavy rope or cable 7 within the receptacle 2.

The end of the heavy cable 7 which extends into the receptacle 2 through the slot 5 may rest upon a suitable supporting bracket 26, which extends transversely of the interior of the receptacle 2, upon which bracket the float 21 also rests until released.

The heavy and light cables, 7 and 24, may be suitably marked to indicate feet or fathoms so that after the float reaches the top of the water in which it is released, this cable will indicate the depth of the water in which the ship carrying the receptacle 2 lies.

From the foregoing description it will be readily apparent that when a ship, as for example, a submarine is sunken the crew imprisoned therein, having access to the shaft 14 may manipulate the same to swing the cover 10 from over the end of the receptacle 2, releasing the float member 21, which will rise to the surface unreeling as it goes the light line or cable 24 from the reel housed therein. The float after reaching the top of the water will then act as a buoy until taken up by a rescue party who may then take in the light line 24, which operation will result in the drawing to the surface of the heavy cable 7, the free end of the cable being removed from the receptacle 2 through the slot 5 as will be readily understood.

The other end of the heavy cable 7 may be secured to the body of the vessel and after the end attached to the light line 24 has been drawn to the surface a fixed connection will be established between a rescue vessel at the surface and the sunken vessel.

Having described my invention, what I claim is:

1. A sunken vessel indicating device, comprising a receptacle designed to be secured to the body of a ship, a cover plate pivotally mounted to shift horizontally over one end of the receptacle, an operating crank, a connecting link between the crank and the cover plate, an operating shaft controlling the crank, said cover plate having a slot therein and receiving said shaft when the plate is moved to open receptacle position, a float designed to be housed within the receptacle, a light line and a reel device within the float for carrying said light line, said light line being extended from the float and secured at one end within the receptacle.

2. A sunken vessel indicating device, comprising a receptacle designed to be secured to the body of a ship, a cover plate pivotally mounted to shift horizontally over one end of the receptacle, an operating crank, a connecting link between the crank and the cover plate, an operating shaft controlling the crank, said cover plate having a slot therein and receiving said shaft when the plate is moved to open receptacle position, a float designed to be housed within the receptacle, a light line and a reel device within the float for carrying said light line, said light line being extended from the float, a heavy cable designed to have one end secured to a vessel and having its other end extending into the receptacle, said other end of the heavy cable having said light line attached thereto, and means for permitting the withdrawal of the heavy cable from the receptacle.

3. In a sunken vessel indicator, a float, a reel housed in said float and carrying a line extending through the float, a receptacle designed to be secured to the body of a vessel and adapted to house said float, the recep-

tacle having an open top and a slot in the wall thereof to receive an adjacent cable connected with said line, a cover pivotally mounted to swing transversely and close the top of the receptacle, a crank having an arm and a shaft, the arm being pivotally mounted adjacent the receptacle to extend to the interior of the vessel, and a link connecting the arm at its free end with the cover at a point adjacent the edge and normally remote from the crank.

In testimony whereof I hereunto affix my signature.

JOHN P. CARELL.
